United States Patent Office

Des. 191,824
Patented Nov. 28, 1961

191,824

NAPKIN CLIP

Vincent C. Dollins, 601 N. High, Independence, Mo.

Filed Dec. 30, 1960, Ser. No. 63,410

Term of patent 7 years

(Cl. D17—9)

FIG. 1.

FIG. 2.

FIG. 3.

FIG. 1 is a side elevational view of a napkin clip embodying my design, the opposite side being a mirror image of the side shown.

FIG. 2 is an end elevational view thereof.

FIG. 3 is a bottom plan view thereof.

I claim:

The ornamental design for a napkin clip, as shown and described.
